UNITED STATES PATENT OFFICE.

THEODORE F. BIGELOW, OF AMSTERDAM, NEW YORK.

FOLDING UMBRELLA.

No. 864,945

Specification of Letters Patent.

Patented Sept. 3, 1907.

Application filed November 21, 1906. Serial No. 344,491.

To all whom it may concern:

Be it known that I, THEODORE F. BIGELOW, a citizen of the United States, residing at Amsterdam, in the county of Montgomery and State of New York, have invented certain new and useful Improvements in Folding Umbrellas, of which the following is a specification, reference being had therein to the accompanying drawing.

My invention relates to improvements in knock down or folding umbrellas of that class in which the ribs, braces and handle are composed of slidably engaged sections.

The object of the invention is to provide an umbrella of this character which will be simple in construction, strong and durable in use, and very convenient and easy to operate.

Further objects and advantages of the invention, as well as the structural features by means of which these objects are attained, will be made clear by an examination of the following specification, taken in connection with the accompanying drawings, in which,

Figure 1 is a side elevation of the handle, one of the ribs and one of the braces of my improved umbrella, showing them in their extended or opened positions; Fig. 2 is a similar view showing the rib and braces in their closed or folded positions; Fig. 3 is a similar view showing said parts folded or collapsed; Fig. 4 is a cross-sectional view through one of the sections of the handle; Figs. 5 and 6 are detail views showing the manner in which the upper ends of the ribs are connected to the handle; Figs. 7, 8 and 9 are detail views showing one of the joints between two adjacent sections of one of the ribs; Figs. 10 and 11 are detail views showing the joint or connection between one of the ribs and its brace; Figs. 12 and 13 are detail views of the spring catch upon one of the braces; Fig. 14 is a cross-sectional view through one of the braces showing the manner in which its two sections are slidably engaged and also showing the manner in which the sections of one of the ribs fold within the sections of its brace; Fig. 15 is a detail longitudinal section through a portion of the handle showing one of its spring catches; Figs. 16 and 17 are detail views of the sliding sleeve and notched ring to which the inner ends of the braces are connected; and Fig. 18 is a detail view of the tip of one of the ribs.

In the present embodiment of my invention, the handle 1 is composed of five similar tubular sections 2, each of the ribs 3 is composed of four similar sections 4, and each of the braces 5 is composed of two similar sections 6; but it will be understood that each of these parts may consist of a greater or less number of sections. While I have shown in the drawings the handle sections 2 in the form of telescoping tubes of circular shape in cross-section, I preferably make them of octagonal shape in cross-section, as shown in Fig. 4, or

of some other polygonal shape so that said sections cannot turn or shift axially upon each other. The handle sections are adapted to telescope one within the other, as shown in Fig. 3, when the umbrella frame 60 is collapsed, and they are held in their extended positions when the umbrella is opened, as shown in Fig. 1, by means of spring catches 7, such as the one shown in Fig. 15. This spring catch comprises a button or stud 8 upon one end of a leaf spring 9 which has its other 65 end soldered or otherwise secured at 10 within one of the handle sections. The button 8 is adapted to be projected by the spring through alining apertures 11 formed in the adjacent handle sections so as to prevent one from sliding upon or telescoping the other. The 70 outer end of the button 8 is tapered or cone-shaped, as shown at 12, so that when it is pressed inwardly to a slight extent and the two handle sections are pushed together, the telescoping movement of one of the sections will force the button entirely within the other, 75 thus permitting the handle sections to readily telescope.

In the outer end of the largest handle section 2 is provided a suitable knob or hand-grip 13 and in the corresponding end of the smallest section 2 is provided a 80 knob, button or other device 14 which may serve as a hand piece.

The rib sections 4 are also of tubular form and preferably of horseshoe shape in cross-section with longitudinal openings in their bottom faces. These sections 4 telescope one within the other when the umbrella frame is collapsed and when it is opened or extended the ribs are prevented from telescoping each other by providing them with lock joints 15, similar to the one shown in Figs. 7, 8 and 9. This joint comprises a notch or seat 16 stamped in one end of one of the rib sections and adapted to receive the adjacent end of the other rib section. On said end of the latter are formed laterally projecting ears 17 adapted to engage a cross-piece 18 upon the other rib section, so as 95 to prevent the two rib sections from being entirely separated. The ears 17 are adapted to project through and slide in the longitudinal openings or slots in the rib sections when the latter have their axes in longitudinal alinement, or in a position to permit them to telescope within each other. When the rib sections are pulled out of each other they assume a slight angular position with respect to each other so that one end of each of them drops into the notch or seat 16 in one end of its adjacent section, as will be readily understood 100 upon reference to Figs. 1, 7 and 8 of the drawings.

In the outer end of the smallest or outermost rib section 4 is provided a cross-piece or tip 20 and the inner end of the largest and innermost rib section formed with a reduced apertured lug or eye 21 by means of 110 which it is pivoted in a notched disk or head 22 fixed upon the upper or outer end of the smallest handle sec-

tion 2. This disk 22, as clearly shown in Figs. 5 and 6, is formed with radially arranged slots or notches 23 to receive the eyes 21 and with an annular groove 24 arranged in its periphery and intersecting the notches 5 or slots 23, so as to receive the pivot wire 25, which passes through the eyes 21.

The telescoping brace sections 6 are preferably of U-shape in cross-section and of sufficient size to receive the rib sections 4 (as shown in Figs. 2, 3 and 14) when the umbrella frame is closed and folded. The edges of the inner section of each brace are bent inwardly, as shown at 26, around the edges of the outer section, so as to guide said sections in their sliding or telescoping movement. The sections of the brace are held in their extended positions by a spring catch 27, which is clearly shown in Figs. 12 and 13, and which is similar in construction to the spring catches 7 previously described. The outer end of the outer brace section 6 has a sliding pivotal connection with its rib 20 through the instrumentality of a substantially U-shaped wire loop bail 28. This loop or strap is adapted to surround and slide upon the rib and has its ends 29 bent outwardly and pivoted in apertures 30 formed in the beveled end of said brace section. The latter is prevented from sliding off of the second section of the rib by a strap 31 fixed upon said section, as clearly shown in Fig. 10. The inner end of the inner brace section 6 is formed with an apertured ear, or eye 32 which is pivoted in one of the notches 33 of a ring or disk 34 provided upon a collar or sleeve 35 which is moved up and down upon the handle in opening and closing the umbrella frame. The ring 34 has an enlarged upper portion formed in its outer edge with curved notches or recesses 36 which are adapted to receive the brace sections and which communicate with said notches 33, the latter being formed in the lower reduced portion of said ring 34. This lower reduced portion of the ring is formed in its periphery with an annular groove which intersects the notches 33 and is adapted to receive the pivot wire 37 which passes through the ears 32, as will be readily understood upon reference to Figs. 16 and 17.

In the sleeve 35 is formed an aperture 38 adapted to receive spring catches or buttons on the handle. When the umbrella is opened, as shown in Fig. 1, the sleeve 35 fits on a fixed collar or sleeve 39 upon the upper end of the second handle section, and its aperture 38 is adapted to receive the uppermost spring catch or button 7 on the handle so that the umbrella will be held in this open position. When the umbrella is closed, as shown in Fig. 2, the aperture 38 in the sleeve 35 receives the spring catch or button 7 which locks the fourth and fifth handle sections in their extended positions. When the umbrella is entirely collapsed, as shown in Fig. 3, said aperture in the sleeve 35 is adapted to receive a button 40 located in the fifth handle section adjacent to the hand piece 13. This button 40 is similar to the button 7.

When the umbrella is in the position shown in Fig. 2, the two outermost rib sections 4 lie within the brace sections 6 and the extreme outer end of the outermost rib section 4 projects beyond the beveled inner end of the inner brace section 6 and through one of the recesses or notches 36 in the ring 34 so that the tip 20 upon said rib section engages the bottom face of said

ring, as clearly shown in Figs. 2, 3 and 17 of the drawings. The cross piece or tip 20 of the rib is made of greater length than the notch or recess 36 so that in opening the umbrella from its position shown in Fig. 3 to that shown in Fig. 2, as presently explained, all of the ribs will be pulled out or extended simultaneously with the extension of the handle.

In order to retain the ribs 4 in the notches 36 and the tips 20 in engagement with the ring 34, when the umbrella frame is being extended or collapsed, I preferably mount upon the fifth handle section a cup-shaped disk 41. The latter is adapted to slide longitudinally on said handle section so that it may be moved over the lower end of the sleeve 35 and thus surround the tips 20 and hold them in engagement with the ring 34, as clearly shown in Fig. 3 of the drawings.

The umbrella frame may be provided with a covering of any description which is attached to the outer ends or tips of the ribs and to the upper or outer end of the handle, so that when the frame is collapsed the covering may be folded or twisted around it and thus produce a very compact bundle.

When it is desired to close the umbrella from its positions shown in Fig. 1 to that shown in Fig. 2, the uppermost spring catch 7 is pressed into the handle 90 sufficiently to disengage its pointed end from the aperture 38 in the sleeve 35. The latter may then be slid downwardly upon the handle until it telescopes the upper end of the fifth handle section and its aperture 38 receives the lowermost catch 7. In this connection it will be noted that the intermediate spring catches 7 may be located out of longitudinal alignment with the two endmost spring catches, if desired. When the sleeve 35 is thus moved, the braces 5 will draw the ribs together and into a parallel position with respect to 100 both the handle and the braces, the sections 6 of the latter receiving the two outermost rib sections 4, as above stated. When it is desired to collapse the frame, as shown in Fig. 3, the lowermost catch 7 is pressed inwardly to release the three parts which it connects, 105 namely, the fourth and fifth handle sections and the sleeve 35. The fifth handle section is then telescoped into the fourth one and the aperture 38 in the sleeve 35 receives the catch 40. At the same time the cup-shaped disk 41 surrounds the sleeve 35 and the tips 20 of the ribs and holds both the ribs and the braces in parallel relation with respect to each other and the handle. The inner sections of the braces 6 are then pressed against the fourth handle section so that the spring catches 27 in said braces and the spring catch 7, 115 which unites the third and fourth handle sections, will be pressed inwardly to release the parts which they unite or lock together. When said catches are thus released the handle section 4 may telescope the handle section 3 and the inner sections 6 of the braces may telescope the outer sections of the same. As this is done, the outermost sections 4 of the ribs will telescope the next adjacent sections. In a similar manner the remaining sections of the handle are successively collapsed by pressing the braces against the handle so that the spring catches 7 are released to permit the sections which they unite to be telescoped.

When it is desired to extend the umbrella frame from its position shown in Fig. 3 to that shown in Fig. 2, the handle 14 is grasped in one hand and the handle 13 and 130

- ring 34 in the other hand, and the parts are then pulled apart. Owing to the engagement of the tips 20 of the ribs 4 with the lower face of the ring 34, it will be seen that the latter draw out or extend the ribs when the handle and braces are extended. Owing to the polygonal, cross-sectional shape of the handle sections, the catches 7 will spring into their respective openings 11 and thus prevent the handle sections from being pulled entirely apart.
10. Having thus described my invention, what I claim as new and desire to secure by Letters Patent of the United States is:—
1. An umbrella of the character described having slidably engaged handle sections, slidably engaged rib sections, slidably engaged brace sections, the sections of said handle, ribs and braces being foldable to positions in parallel relation to each other, a notched ring upon the handle sections formed in its periphery with notches adapted to receive the ends of the outermost rib sections, the cross pieces 20 upon the tips of said outermost rib sections, said cross pieces being of greater length than the width of the notches in said ring and being adapted to engage the bottom face of said ring, and a cup-shaped disk slidable upon one of the handle sections and adapted to engage and close the cross pieces 20 to hold the latter in engagement with the bottom face of the notched ring, whereby the slidably engaged sections of the handle, braces and ribs may be simultaneously extended, substantially as described.
  2. An umbrella of the character described, having a handle composed of telescoping sections, ribs pivoted at their upper ends to the uppermost handle section and composed of telescoping sections, cross pieces upon the tips of said ribs, a notched ring slidable upon said handle sections, braces pivoted to said notched ring and composed of telescoping sections, wire bail upon the outer ends of said braces and slidably engaged with said ribs, and a cup-shaped disk upon the lowermost handle section adapted to hold the cross pieces on the tips of said ribs in engagement with said notched ring, whereby the sections of the handle, braces and ribs may be simultaneously extended, substantially as shown and described.
  3. An umbrella of the character described having a sectional handle, sectional ribs, a sliding sleeve on the handle, braces consisting of slidably engaged sections, catches for holding the sections of said braces in their extended position, pivotal connections between the inner ends of the braces and said sleeve and sliding and pivotal connections between the outer ends of the braces and said ribs.
  4. An umbrella of the character described having its handle, ribs and braces composed of slidably engaged sections foldable to positions in parallel relation to each other, means upon said handle for receiving and holding the ribs when in parallel relation therewith, spring catches arranged upon the handle for locking its sections extended, said catches having projecting portions adapted to be engaged and operated by the braces when the latter are pressed inwardly against the handle, and spring catches upon the braces for holding their sections extended, the last mentioned catches being arranged upon the inner faces of the braces and having projecting portions adapted to engage the handle and to be actuated thereby when the braces are pressed inwardly against the handle, substantially as described.
  5. An umbrella of the character described having its handle, ribs and braces composed of slidably engaged sections foldable to positions in parallel relation to each other, a notched ring upon said handle to guide said braces and ribs when in such parallel position, a cup-shaped disk slidable upon said handle and adapted to engage the tips of the ribs when said parts are engaged with said notched ring, and spring catches upon said braces and said handle for holding their sections in extended positions, said catches being arranged upon the opposing faces of the handle and braces whereby they will be released when the braces are pressed against the handle, substantially as shown and described.
  6. An umbrella of the character described having slidably engaged handle sections formed with apertures, spring catches for holding said sections extended, said catches consisting of springs arranged within the handle sections and carrying radially projecting studs adapted to project through the apertures in the handle sections and formed with tapered outer ends which latter project beyond the outer faces of the handle sections, and braces adapted to be pressed against said projecting ends of the studs to move the catches to their released position, substantially as described.
  7. An umbrella of the character described comprising a handle, ribs, braces between said handle and ribs and composed of slidably engaged sections, and fastening devices upon said braces for holding their sections extended, said fastening devices having inwardly projecting portions adapted to engage the handle and to be thereby moved to released position when said braces are pressed inwardly against said handle, substantially as described.
  8. An umbrella of the character described, comprising a handle, ribs, braces between said handle and ribs and composed of slidably engaged sections, and catches upon said braces for holding their sections extended, and catches having portions projecting laterally beyond the outer surfaces of the braces for holding their sections extended, said catches being adapted to be moved into the braces to released positions when pressed against said handle, substantially as described.
  9. In a folding umbrella, a rib composed of telescoping sections having longitudinally extending slits, one of said sections having the seat 16 stamped in it and the cross piece 18 closing the slit adjacent to said seat, and the other section being adapted to enter said seat and having the stop 17 to engage the cross piece or stop 18, substantially as described.
  10. In a folding umbrella, a rib composed of slidably engaged sections, a brace of substantially U-shape in cross-section having its open side turned outwardly to permit the sections of said rib to fold into it, a U-shaped bail pivoted upon the outer end of said brace and surrounding said rib for sliding movement thereon, and a band surrounding one of the rib sections to serve as a stop to limit the sliding movement of the brace upon said rib section, substantially as described.
- In testimony whereof I hereunto affix my signature in presence of two witnesses.
